UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,536, dated December 31, 1889.

Application filed December 6, 1889. Serial No. 332,828. Term of patent $3\frac{1}{2}$ years.

To all whom it may concern:

Be it known that I, WILLIAM K. BENEDICT, of the city, county, and State of New York, have invented and produced a new and original Design for the Exterior of a Residence, of which the following is a specification, reference being had to the accompanying drawings, forming a part thereof.

Figure 1 represents a perspective view of a residence showing my design. Fig. 2 represents a horizontal section or plan of the first story. Fig. 3 represents a horizontal section or plan of the second story.

Similar letters of reference designate corresponding parts in all the figures.

A residence embodying my design comprises a first and second story and an attic story. The first story at the front is shown as provided with a porch A extending wholly across the front. This porch is supported by an ogee-shaped roof B. Upon one side of the residence there is an octagonally-shaped bay C, which extends through both the first and

second stories, and is surmounted by a balcony D. To the rear of the bay C, upon the first story, is a porch E, surmounted by a shed-roof F.

At the front of the residence and upon the second story is an octagonally-shaped bay G, surmounting the roof B. The residence is surmounted by a gable roof I, which extends from the front to the rear of the residence, and is provided at the front with an overhanging portion J, extending over the bay G. Between the overhanging portion J and the front at the second story are consoles K. Upon the side of the residence (shown more clearly in Fig. 2) is an L portion K.

What I claim is—

The design for the exterior of a residence, substantially as herein shown and described.

WILLIAM K. BENEDICT.
